Primary Examiner — Keith J Wilson*(74) Attorney, Agent, or Firm* — Daryl R. Wright; Greg Carr(57) **CLAIM**

We claim the ornamental design for a model vehicle winch remote, as shown and described.

DESCRIPTION

FIG. 1 is an upper, left, front perspective view of a model vehicle winch remote showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an upper plan view thereof;

FIG. 7 is a lower plan view thereof; and,

FIG. 8 is a lower, right, rear perspective view of the model vehicle winch remote.

In the drawings, the broken lines illustrate portions of the model vehicle winch remote that form no part of the claimed design.
